(57) **CLAIM**

The ornamental design for a light fixture, as shown and described.

DESCRIPTION

This application is related to commonly assigned, concurrently filed application Ser. No. 29/252,130, the full disclosure of which is incorporated herein by reference.

FIG. 1 is a perspective view of a first embodiment of the light fixture of the present design;

FIG. 2 is a front elevation view thereof, the right side, rear and left side elevation views being identical thereto;

FIG. 3 is a top plan view thereof;

FIG. 4 is a bottom plan view thereof;

FIG. 5 is a front elevation view of a second embodiment; and,

FIG. 6 is a front elevation view of a third embodiment.

The broken line showing is for illustrative purposes only and forms no part of the claimed invention.
